Attorney.

UNITED STATES PATENT OFFICE.

WILLIAM A. KIBBE, OF LEAVENWORTH, KANSAS, ASSIGNOR TO MARTIN A. NORTON, OF SAME PLACE.

MARKING IMPLEMENT.

SPECIFICATION forming part of Letters Patent No. 297,812, dated April 29, 1884.

Application filed August 18, 1883. (Model.)

To all whom it may concern:

Be it known that I, WILLIAM A. KIBBE, a citizen of the United States of America, residing at Leavenworth, in the county of Leavenworth and State of Kansas, have invented certain new and useful Improvements in Marking Implements; and I do hereby declare the following to be a full, clear, and exact description of the invention, such as will enable others skilled in the art to which it appertains to make and use the same, reference being had to the accompanying drawing, and to letters or figures of reference marked thereon, which forms a part of this specification.

15 This invention relates to striping and marking devices for painters; and it consists of certain improvements on the device described in Letters Patent No. 279,767, granted to me June 19, 1883, whereby the general form and construction of the device mentioned in said patent is simplified and cheapened, and at the same time rendered more effective in operation.

20 In the accompanying drawing, the figure 25 represents a vertical section of a striping and marking device having my improvements embodied therein.

For a general understanding of the nature and objects of the invention, reference may be 30 had to the Letters Patent above recited.

In the accompanying drawing, A represents a cylindrical chamber adapted to contain the paint or marking-fluid, and the said chamber is contracted at its upper and lower ends, a b.

35 Attached to the lower end, b, is a tube, B, contracted at its lower end and provided with an opening, c, therein, for the passage of the brush C, which is connected to a brush-holding rod or tube, D, which extends up through the tube B and chamber A, and is connected at its upper extremity to a cross-plate, d, secured to a nozzle, E, across the mouth of the same.

45 Centrally around the outer side of the nozzle E is a milled rib, e, for facilitating the manipulation of the nozzle, and the said nozzle is exteriorly threaded below and above said milled rib e, the threaded portion below being adapted to engage the interiorly-threaded portion f of the contracted top a of the chamber A for the attachment of the noz-

zle thereto, while the threaded portion of the nozzle above the milled rib is adapted to receive an interiorly-threaded cap, F, for closing the mouth of the nozzle.

55 Centrally on the brush-holding tube D is a piston or washer, G, which, when the brush is entirely out of the tube B, rests on the upper portion of the said tube B, but is withdrawn from the said tube B into the chamber A when the paint-brush is partially within the tube B, so that the paint can freely flow to the same.

60 It is desirable to so arrange the piston or washer G on the brush-holding tube that said washer can be removed from the tube B to admit the paint to the said tube B, and the washer then moved into the same, so that by manipulating the threaded nozzle the piston descends with the rod D in the tube B and feeds the paint to the brush until the same is entirely without the tube B, and the end of the rod D arrives at the mouth of the tube B and cuts off the further flow of paint.

65 From the foregoing it will be apparent that by the simple rotation of the threaded nozzle the brush, with its holding-tube, will be caused to descend or ascend, and the use of retracting spring levers and stops dispensed with.

70 I claim—

1. The combination, in a paint striping and marking machine, of the reservoir A, tube B, and threaded nozzle E, connected to the brush-holding tube extending down through the reservoir A into the tube B, and carrying the marking-brush at its lower end, substantially as set forth.

2. The combination, in a paint marking and striping machine, of a reservoir, A, and tube B, and threaded nozzle E, having milled rib e and cap F, and connected to the upper end of the rod D, extending down into the tube B, and carrying the piston G and the marking and striping brush, substantially as described.

90 In testimony whereof I affix my signature in presence of two witnesses.

WILLIAM A. KIBBE.
